PNEUMATIC THREAD HOLDER FOR WEFT
REPLENISHING LOOMSGabriel C. Beatrice, Shrewsbury, Mass., assignor
to Crompton & Knowles Loom Works, Worcester,
Mass., a corporation of Massachusetts

Application February 24, 1951, Serial No. 212,577

13 Claims. (Cl. 139—256)

1
This invention relates to improvements in weft replenishing loom pneumatic thread holders adaptable more particularly to locate the thread of a freshly transferred shuttle first in a position favorable for self-threading of the shuttle and then in a position favorable for proper cooperation with a filling fork on the loom lay.

Many looms are provided with a filling fork pivoted on the front of the lay to detect presence or absence of the weft in the warp shed. When a shuttle in such a loom is replenished with fine or glossy weft there is likelihood that the fork will slide off the weft on the first pick after the shuttle is replenished and thereby cause an unnecessary stoppage of the loom. In order to enable the shuttle to effect self-threading it is desirable that the holder for the thread be more or less aligned with the lay at the time of picking. If the thread holder were left in this position, however, the weft of the freshly replenished shuttle might be so far back that it could not support the filling fork.

In a form of thread control mechanism which has gone into general use on certain types of looms the weft ends from reserve bobbins in the magazine are led into a pneumatic intake mouth of a thread holder and thence to a thread collector or accumulator. When the thread of a replenished shuttle is cut at the selvage it is drawn through the intake mouth and into the accumulator. It has been proposed heretofore to move both the thread holder and the thread accumulator bodily in a backward and forward direction for the purpose of locating the holder in a rear position at the time of picking and thereafter locating it forwardly to enable the thread to be moved under the filling fork. It is an important object of the present invention to provide a substantially stationary thread accumulator and mount the thread holder for back and forth motion on a combined support and pneumatic connection between the thread holder intake mouth and the interior of the accumulator.

It is a further object of the invention to mount the thread holder on a tube which is slidable with respect to the base or supporting structure of the thread accumulator, the tube enabling a thread entering the intake mouth to pass through it and into the accumulator.

It is a further object of the invention to provide a tube held in forward position by resilient means, such as a compression spring around the tube, so that the thread holder will be in a position favorable for moving the thread of a freshly replenished shuttle under the filling fork and

2
then temporarily moving the tubular member rearwardly to facilitate self-threading of the shuttle while maintaining pneumatic communication between the member and the accumulator. The tubular member is then returned to its forward position by the spring to await another replenishing operation of the loom.

The tubular member may be cylindrical and tend to turn in the slide bearing for it on the supporting structure for the accumulator, and it is a further object of the invention to provide a guide carried preferably by a stationary part of the mechanism and engaging the tube to prevent rotation of it with respect to the bearing so that a lateral opening in the tube can be kept in correct register with a port or air and thread inlet in the base of the thread accumulator.

With these and other objects in view which will appear as the description proceeds, the invention resides in the combination and arrangement of parts hereinafter described and set forth.

In the accompanying drawings, wherein two forms of the invention are set forth,

Fig. 1 is a side elevation of part of the weft replenishing loom having the preferred form of the invention applied thereto,

Fig. 2 is an enlarged plan view looking in the direction of arrow 2, Fig. 1, showing the thread holder in its normal forward position, the thread accumulator cup being in cross section,

Fig. 3 is an enlarged vertical section on line 3—3, Fig. 2, showing the thread holder in its normal forward position,

Figs. 4 and 5 are enlarged vertical sections on lines 4—4 and 5—5, respectively, of Fig. 3,

Fig. 6 is a sectional view similar to the right hand part of Fig. 3, but showing the tubular member in the position which it occupies when moved rearwardly to facilitate self-threading of the shuttle,

Fig. 7 is a view similar to part of Fig. 2, but on an enlarged scale, showing a modified form of the invention,

Fig. 8 is a vertical section on line 8—8, Fig. 7.

Fig. 9 is an enlarged vertical section on line 9—9, Fig. 7,

Fig. 10 is a vertical section on line 10—10, Fig. 9,

Fig. 11 is a diagrammatic view showing the loom lay in front center position in full lines and in picking position in dotted lines the thread holder being indicated in rear position, and

Fig. 12 is a diagrammatic view showing the thread holder returned to its normal forward position with the thread of a freshly replenished shuttle under the filling fork of the loom.

Referring particularly to Fig. 1, the loom frame

1 supports top and bottom shafts 2 and 3, respectively, which may be geared together by connections not shown to cause the bottom shaft to rotate once for every second rotation of the top shaft. The loom lay 4 is reciprocated backwardly and forwardly by connectors 5 attached at their rear ends to the crank shaft 2. The lay is provided with a shuttle box 6 to receive a shuttle S. Part of a picking mechanism is shown in Fig. 1, this part being a picker stick 7 which is actuated when the lay is moving rearwardly to propel the shuttle to the opposite side of the loom.

In the present instance the loom is adapted for the automatic weaving of a fabric having two different kinds of weft and is provided with a magazine M having front and back stacks 10 and 11, respectively, of reserve bobbins from which weft ends W extend to a thread holder designated generally at H. A transerrer arm 12 of usual construction is provided to transfer the lowest bobbin in one or the other of the stacks into the depleted shuttle, depending upon the position of the magazine. The latter is pivoted as at 13 on a fixed support 14 and is connected by a train of mechanism designated generally at 15 to rock the magazine so that transfer can occur from either bobbin stack.

A lever 16 is rocked about a fixed stud 17 by a cam 18 on shaft 3. A normally stationary setting lever 19 is rocked in a clockwise direction about stud 17 by lever 16, Fig. 1, when a weft replenishing operation of the loom is to occur, thereby lowering that part of lever 19 behind, to the right in Fig. 1, stud 17.

A stand 25 fixed to the loom frame has mounted thereon a pulley 26 around part of which is trained a flexible cord or cable 27 the lower end of which is attached to a turnbuckle 28. A spring 29 having its lower end connected to that part of lever 19 behind the stud 17 has its upper end connected to the lower end of the turnbuckle. A part of the cable 27 extends forwardly as at 30. The loom is provided with an air pump 35 connected to a hose 36 which leads to a thread accumulator A which includes a cylindrical cup 37.

During loom operation the air pump creates sub-atmospheric pressures within the cup 37 during the backward stroke of the lay, to the right as viewed in Fig. 1, and if a replenishing operation is to occur the parts 30 of cable 27 will move rearwardly. This will generally occur while the lay is moving forwardly or at least is in the rear part of its range of motion. After the bobbin transfer the lay moves rearwardly from the position shown in Fig. 1 and the rear end of lever 19 will move upwardly and be reset to its normal high position before the lay next reaches its front center position.

The matter thus far described may be substantially the same as that shown for instance in prior Patent No. 2,531,177, and operates in usual manner except as noted hereinafter.

In carrying the preferred form of the present invention into effect the stand 25 has secured thereto a bracket 40 to which a support means 41 is bolted as at 42 in stationary position. This support means includes a base 43 adapted to receive the lower end of the accumulator cup 37. The base has an air and thread inlet port 45 extending downwardly from the cup 37 and communicating with a horizontal bore 46 in a bearing 47 formed preferably as an integral part of the base and extending backwardly and forwardly with respect to the loom.

Slidable in the bearing is a tubular member 50

preferably circular in cross section and having an air and thread passage 51 therethrough the left end of which as viewed in Fig. 3 is in pneumatic communication with a thread intake mouth 52 of the thread holder H. The latter may be formed with a collar 53 fixed to the tube in any approved manner. A compression spring 55 surrounds that part of the tubular member 50 between the forward end of bearing 47, the left as viewed in Fig. 3, and the collar 53. This spring is normally expanded and maintains the thread holder H in a forward position as shown in Figs. 1 and 3.

The tube 50 has a part thereof within the bearing 47 cut away to form an elongated upwardly facing opening 56 which is always in pneumatic communication with the port 45. The right end of the tube 50 extends beyond the port 45 and has secured therein a plug 58 closing the rear end of the tube and attached to a fitting 59 the left end of which as viewed in Fig. 3 is tapped into the plug. The right end of the fitting 59 is connected as at 60 to the previously mentioned part 30 of cable or cord 27.

In order to prevent the cylindrical tube 50 from turning in the bearing 47 a guide 65 is secured as at 66 to the base 43 and extends down through the port 45 and opening 56 and engages the right and left side walls 67 and 68, respectively, of the tube 50 extending along the opening 56, see Fig. 5. The guide substantially closes the right end of the tube as viewed in Fig. 3 in addition to preventing rotation of the tube in the bearing 47. Stop collar 70 on plug 58 is positioned to engage the rear end of bearing 47 and limit forward motion of tube 50.

In the operation of the preferred form of the invention the parts will normally be in the position shown in Figs. 1 and 3 with the spring 55 fully expanded to hold the stop collar 70 against the right end of bearing 47, see Fig. 3. In this position of the parts the thread holder H will be at the forward end of its range of motion and the weft ends W will pass into the intake mouth 52, through the bore or passage 51, up from the opening 56 through the port 45 and into the interior of the thread accumulator cup 37. Sub-atmospheric pressures within the latter will hold the threads or weft ends as indicated in Fig. 3 and whenever one of these ends is cut at the selvage following a transfer of the corresponding bobbin the thread will be pneumatically drawn into the accumulator.

Whenever a replenishing operation occurs the bobbin transfer mechanism, and if necessary the magazine, will be set by rocking of lever 19, and at the same time there will be a downward pull on the cable 27 so that the tubular member 50 will slide rearwardly to the position shown in Fig. 11. The opening 56 is of sufficient length so that when the thread holder and the tube 50 are in their rearmost positions the interior passage 51 of the tube will still be in pneumatic communication with the port 45. This position of the tube and its opening, indicated in Fig. 6, will be assumed by the parts prior to the time the lay reaches its front center position indicated in full lines in Fig. 11. When the lay reaches front center the shuttle S will be replenished and the thread T of the freshly transferred bobbin will extend diagonally rearwardly to the thread holder. The lay will then move rearwardly to the dotted line position Fig. 11, at which time the shuttle will be picked toward the opposite side of the loom while the holder H is in a position

favorable for self-threading by thread T. When in flight across the lay the shuttle will pass a filling fork F of the usual center type and lever 19 will start to return to its normal position, whereupon cable 27 will be slackened and the spring 55 will expand to move the thread holder H to its forward position, thereby moving the thread T of the freshly transferred shuttle under the fork F.

From the description of the construction and operation of the preferred form of the invention it will be understood that the tube 50 provides a combined sliding support for the holder H and an air passage between the intake mouth 52 and the port 45, and that the opening 56 will be of sufficient length to afford pneumatic communication between the intake mouth 52 and the port 45 throughout the sliding range of motion of the tube 50 in the bearing 47. The rearward motion of the thread holder will ordinarily be sufficient to close the coils of the spring 55 so that the latter acts as a stop to limit any further rear motion of the tube 50, whereupon the spring 29 will expand to accommodate any excess motion of the lever 19. From this it will be understood that the spring and the collar 53 jointly constitute stop means to limit the range of sliding movement of the tube 50 in the bearing 47.

It will not be necessary in all instances, however, to rely upon the spring as a stop to limit rearward movement of the holder H. When the thread holder is in its forward position as in Fig. 3 it and the tube 50 on which it is mounted may be considered as being in its extended position, but when the tube moves rearwardly to some such position as shown in Fig. 6 these parts may then be considered as being in their retracted position, the tube moving from one to the other of these positions along its axis as defined by the bore of the bearing 47.

The plug 58, fitting 59, and the cable 27 may be considered as operating means for the tube 50 connected to the lever 19, but certain features of the invention are independent of the particular means for moving the operating means and it will be sufficient if any other means is provided which will give the thread holder and tube 50 the motions already described at approximately the times in the loom cycle set forth hereinbefore.

In the modified form of the invention much of the mechanism thus far described can be used. The thread holder is mounted on a tube 80 similar to tube 50 but having a relatively short laterally and upwardly facing opening 81 communicating with an elongated slot-like port 82 in the bottom of a base 83 otherwise similar to base 43. In this modified form of the invention the tube 80 will move from its forward extended position with the opening 81 at the left of the port 82 as shown in Fig. 7 to a retracted or rearward position with the opening 81 near the right end of the elongated port 82 when the operating mechanism moves the tube 80 rearwardly.

In order to prevent turning of the tube 80 in the bearing 47 the plug 58 may have secured thereto a collar 90 through which extends a guide pin 91 anchored as at 92 into the base 83. The collar 90 serves as a stop to limit forward motion of the tube 80 and by its engagement with the guide pin 91 holds the opening 81 in register with the port 82.

It is customary to provide the thread accumulator with a vertical rod around which the weft ends in the cup 37 may be wrapped. Ordin-

narily this anchorage rod for the threads is coaxial with the cylinder or cup 37, but it is desirable in the modified form of the invention to have this rod, indicated at 95, spaced sufficiently from the slot-like port 82 so that there will be only a slight change in the distance between the anchor rod 95 and the opening 81 when the tube goes from its extended to its retracted and then back to its extended position.

From the foregoing it will be seen that the invention sets forth an improved support means for the thread accumulator having a bearing for slidably mounting the tube 50 which not only acts as a support for the holder H, but also by reason of the passage 51 therethrough pneumatically connects the intake mouth 52 with the port 45 leading to the interior of the accumulator A. In both forms of the invention the sliding tube on which the thread holder is mounted can move from its extended forward position to its retracted rear position while maintaining pneumatic communication between the interior of the supporting tube and the port leading to the interior of the accumulator. In the preferred form of the invention the tube has an elongated lateral opening 56 which communicates with the relatively short port 45, whereas in the modified form of the invention the lateral opening in the tube is comparatively short and registers with an elongated port in the base of the accumulator. In the preferred form of the invention the guide 65 prevents turning of the tube 50 and also closes the right hand part of the tube 50 as shown in Fig. 3 to prevent air leakage which might otherwise reduce the effectiveness of the subatmospheric pressures existing in the cup 37. In both forms of the invention the rear end of the tube is closed by plug 58 which further prevents leakage from the atmosphere and also serves as part of the operating means for the sliding tube. It will be understood that in order to prevent leakage in the bore of the bearing around the tubular member the latter should have a fairly close fit with the bore but sufficiently free to enable the spring to return the thread holder to its normal forward position.

Having thus described the invention it will be seen that changes and modifications of the foregoing specific disclosure may be made without departing from the spirit and scope of the invention.

What is claimed as new is:

1. In support means for a weft end thread holder and a thread accumulator in which subatmospheric pressures are created, a base having a part to fit the accumulator and having an air and thread port therein, a bearing on the base having a bore therein, a tubular member having an air and thread passage therein communicating with the intake mouth of a thread holder on the member, the latter being mounted for sliding movement in said bore, said member having an opening therein affording pneumatic connection between said passage and said port, and stop means on the tubular member limiting sliding of the member in said bore to a range of movement throughout which the port is in pneumatic communication with said passage through said opening.

2. The support means set forth in claim 1 wherein a spring yieldingly holds the tubular member at one end of said range of movement.

3. The support means set forth in claim 1 wherein a compression spring surrounds the

tubular member between said bearing and said thread holder and yieldingly holds said member at one end of said range of movement thereof.

4. In support means for a weft end thread holder and a thread accumulator in which sub-atmospheric pressures are created, a base having a part to fit the accumulator and having an air and thread port therein, a bearing on the base having a bore therein, a tubular member having an air and thread passage therein mounted for sliding movement in said bore, said member having an opening therein affording pneumatic connection between said passage and said port and having thereon a thread holder provided with an intake mouth communicating with said passage, a spring urging said member in one direction in said bore, and a stop on the tubular member to engage said bearing and limit movement of said member in said one direction under action of said spring and cooperating with the latter to hold said tubular member with said opening in register with said port.

5. In support means for a weft end thread holder and a thread accumulator in which sub-atmospheric pressures are created, a base having a part to fit the accumulator and having an air and thread port therein, a bearing on the base having a bore therein, a tubular member having an air and thread passage therein mounted for sliding movement in said bore and having thereon a thread holder provided with an intake mouth communicating with said passage, said tubular member being capable of assuming either an extended position relative to said base in which the thread holder is relatively far from said base or a retracted position in which the thread holder is relatively near said base, said member having an opening therein through which said passage is in communication with said port whether the member is in extended or retracted position, and resilient means normally holding the member in extended position but yieldable to enable said member to move to the retracted position thereof.

6. In support means for a weft end thread holder and a thread accumulator in which sub-atmospheric pressures are created, a base having a part to fit the accumulator and having an air and thread port therein, a bearing on the base having a bore therethrough, a tubular member having an air passage therein slidably in said bore, a thread holder on one end of said member at one side of said bearing having a weft end intake mouth communicating pneumatically with said passage, and operating means on the other end of the tubular member on the opposite side of said bearing by which the member can be moved endwise in said bore, and said member having an opening therein between the thread holder and the operating means registering with said port.

7. The support means set forth in claim 6 wherein said operating means closes the end of

the tubular member adjacent thereto to the atmosphere.

8. The support means set forth in claim 6 wherein said tubular member is cylindrical and a guide secured to said base engages the cylinder at the sides of said opening to prevent turning of said cylinder in said bore.

9. The pneumatic thread holder set forth in claim 6 wherein the tubular member is cylindrical and a guide on the base prevents turning of the member about the axis thereof and extends into said bore on the side of the port opposite said thread holder to substantially close said passage.

10. The pneumatic thread holder set forth in claim 6 wherein the tubular member is cylindrical and a guide on the base prevents turning of the member about the axis thereof and extends into said bore on the side of the port opposite said thread holder to substantially close said passage and stop means arrests movement of said tubular member while the part of said opening adjacent to the thread holder is spaced from said guide.

11. The pneumatic thread holder set forth in claim 6 wherein said port is an elongated slot extending in the direction of the length of the tubular member and said opening in the tubular member registers with the port when the member is in a plurality of positions relative to the base.

12. The pneumatic thread holder set forth in claim 6 wherein said opening in the member is elongated and extends lengthwise of the member and the port extends lengthwise of the member for a distance less than the length of the opening, the latter being long enough to register with the port when the member is in any one of a plurality of positions relative to the base.

13. A weft end thread holder mechanism comprising a tubular member having an air passage therein, a weft end thread holder secured to one end of the tubular member having a weft end intake mouth communicating with the end of said passage adjacent to the thread holder, and operating means on the other end of the member closing the other end of said passage to the atmosphere, said member having a lateral opening therein communicating with said passage and located along the length of said tubular member between the intake mouth of said thread holder and said operating means.
